MOUNTING FOR ROCK DRILLS

Dudley W. Hart, Phillipsburg, N. J., assignor to
 Ingersoll-Rand Company, Jersey City, N. J., a
 corporation of New Jersey

Application March 1, 1935, Serial No. 8,830

4 Claims. (Cl. 255—51)

This invention relates to mountings for rock drills, and more particularly to a wheel mounting capable of being readily transported from one drilling site to another.

5 One object of the invention is to enable the rock drill to be readily tilted to any desired degree of inclination with respect to the face of the rock being drilled.

Another object is to enable the rock drill to 10 be conveniently positioned for drilling toe-holes at the foot of a vertical rock face.

Other objects will be in part obvious and in part pointed out hereinafter.

In the accompanying drawings and in which 15 similar reference numerals refer to similar parts,

Figure 1 is a side elevation, partly broken away, of a mounting constructed in accordance with the practice of the invention and a rock drilling mechanism which it supports,

20 Figure 2 is a transverse view taken through Figure 1 on the line 2—2 looking in the direction indicated by the arrows,

Figure 3 is a plan view taken through Figure 1 on the line 3—3 looking in the direction indicated by the arrows,

25 Figure 4 is a plan view of a detail, and

Figure 5 is a perspective view of a detail.

Referring more particularly to the drawings, the mounting, designated by 20, includes in its 30 organization a main frame 21, a column 22 supported by the main frame, and wheels 23 and 24, to support the mounting.

The frame 21 comprises a pair of side members 25 having portions 26 which are arranged in parallelism with respect to each other and converging portions 27 connected at their free ends by plates 28 and 29 disposed on the upper and lower surfaces, respectively, of the members 25. In the plates 28 and 29 is journaled the spindle 30 of a yoke 31 to which the wheel 24 is pivotally secured.

The wheels 23 are connected to the portions 26 of the members 25 by spindles 32 having flanges 33 fastened to the members 25 by bolts 34. Preferably, the free ends of the portions 26 are provided with cross members 35 to which the flanges 33 may be secured in order that the mounting may be shifted along a line parallel to the rock face, thereby avoiding the necessity of 50 tedious shifting to and fro of the mechanism to position the rock drill on a desired line of cut. The cross members 35 are suitably perforated to accommodate the bolts 34.

The column 22 may be of a well known type 55 consisting of a pair of channel members 36 of

which the front legs 37 act as guides for a saddle 38 of a rock drill 39 carrying a working implement 40. A further function of the column 22 is that of a support for a feeding mechanism for the rock drill 39.

5 The feeding mechanism illustrated comprises a cylinder 41 which may be secured to the column 22 in any suitable manner and a piston 42 in the cylinder. The piston has a rod 43 which extends slidably through the upper head 44 of the cylinder 10 and carries a rotatable member 45, illustrated in the present instance as a sheave, which may be multi-grooved to accommodate a pair of flexible members 46 and 47.

The flexible members 46 and 47 are shown, 15 for the sake of simplicity of illustration, as cables. One end of that designated 47 is anchored to an arm 48, at the top of the column 22. It is trained around the under side of the sheave 45, thence over a sheave 49 at the top of the column and is secured with its other end to the upper portion of the saddle 38. Thus, as the piston 42 is actuated downwardly the sheave 45 pulls on the cable 47 and moves the rock drill toward the upper or free end of the column 22.

20 The cable 46 is connected with one end to the head 49 and is trained over the top of the sheave 45. It then extends downwardly over a sheave 50 at the lower portion of the column 22 and its opposite end is connected to the lower portion of the saddle 38. The arrangement is such that when the piston is actuated upwardly the cable 46 is drawn to pull the rock drill to move toward the work in accordance with the penetration of the working implement 40 thereto.

25 The pressure fluid for actuating the piston 42 and the elements connected thereto is controlled by a manually operable valve 51 arranged in the head 44. The pressure fluid may be introduced directly from a source of supply (not shown) 30 into a central bore 52 in the throttle valve. Leading from the bore 52 is a passage or port 53 which in one position of the throttle valve registers with a passage 54, in the head 44 and opening into the upper end of the cylinder 41, and in another position of the throttle valve the port 53 registers with a passage 55 consisting of 35 branches in the head 44 and a lower head 56 of the cylinder and a tube 57 connecting the branches.

40 In the periphery of the throttle valve is a groove 58 to afford communication with either of the passages 54 or 55 and an atmospheric exhaust port 59 in the head 44. Thus, as will be readily understood, when the throttle valve 51 is rotated 45

to bring the port 53 into registry with the passage 54 pressure fluid flows into the upper portion of the cylinder 41 to move the piston 42 toward the head 56 to raise the rock drill 39, and 5 when the port 53 is moved into registry with the passage 55 pressure fluid is introduced into the lower part of the cylinder 41 to raise the piston 42 and thereby cause the rock drill 39 to follow and remain in correct operative relationship with 10 the working implement which it actuates. When the port 53 registers with either the port 54 or 55 the groove 58 will establish communication between the remaining passage 54 or 55 and the exhaust port 59.

15 A specific use of the drilling mechanism so far described is that of drilling vertical holes. When used for that purpose the column 22 is disposed in a vertical position and the holes are drilled in 20 suitably spaced relation with respect to each other along a predetermined line of cut. There are, however, many instances in which the progress of the work may be greatly expedited through the use of horizontal holes or holes inclined with 25 respect to the rock face, as for instance at the foot of a vertical ledge. In order to enable the rock drill to be positioned for such use the column 22 is provided with oppositely extending lateral trunnions 60 which may be secured to the channels 36 as by welding.

30 On the outer or free ends of the trunnions are 35 coniform surfaces 61 which seat against corresponding surfaces 62 of apertures 63 in support plates 64 arranged on opposite sides of the column. Adjacent the coniform surfaces 61 and seating 40 against shoulders 75 on the trunnions are rings or flanges 65 which are disposed loosely on the trunnions and, like the plates 64, are perforated for the accommodation of bolts 66 whereby the coniform surfaces 61 and 62 may be drawn into fixed frictional engagement with each other.

The plates 64 are adapted to swing in vertical planes between the column 22 and the portions 26 of the frame members 25. They constitute the sole connections between these elements and 45 are provided, in their ends which lie adjacent the frame members, with coniform apertures 67 for the accommodation of similarly shaped disks 68 which may be fixedly clamped into the apertures 67 by bolts 69 extending through the disks 68 and 50 the apertures 67 and through bearings 70 affixed to the frame members 25.

Suitable means, such as anchor rods 71, may be provided for holding the mounting immovable 55 against the effects of vibration incident to the operation of the rock drill. The anchor rods have pointed ends 72 which may be driven into the supporting ground or seated in depressions thereof, and in the side members 25 are suitable securing means 73 for the anchor rods. The securing means 73 are illustrated as being in the form of eye-bolts through the eyes of which the rods 71 extend. The eye-bolts are provided with nuts which may be manipulated to draw the rods firmly against the sides of the members 25.

65 In practice, whenever it is desired to drill ver-

tical holes the column is swung to a vertical position in which the axes of the trunnions 60 and the disks 68 lie in substantially the same vertical plane. The bolts 66 and 69 are then tightened to draw the trunnions and the disks 68 into firm frictional engagement with the coniform surfaces of the plates 64. In order to drill inclined holes the bolts 66 and 69 may be loosened and the column 22 rocked to the desired degree of inclination with respect to the rock face.

In the event that it be desired to drill inclined holes at the foot of a vertical rock ledge the bolts are loosened sufficiently to permit rotation of the plates 64 on the disks 68 and the trunnions. The trunnions 60 may then be dropped to a position below the horizontal plane of the disks 68 and the drilling implement 40 may be lowered to the foot of the ledge. After the column 22 has been thus positioned the bolts are again manipulated to draw the plates 64 into firm frictional engagement with the disks and the trunnions.

I claim:

1. A mounting for rock drills, comprising a frame, a guide column, a rock drill slidable thereon, support means for the column and being swingable through the horizontal plane of the frame, pivots for connecting the support means to the frame, other pivots on opposite sides of the column for connecting the support means to the column and being off-set with respect to the first mentioned pivots, and individual clamping means for each pivot to rigidly secure the pivots to the support means.

2. A mounting for rock drills, comprising a frame, a guide column, a rock drill slidable thereon, a pair of support plates arranged on opposite sides of the column and constituting the sole connections between the column and the frame, pivot means on the frame for one end of the support plates, pivot means on the column for the other ends of the support plates and being off-set with respect to the first mentioned pivot means, and means for clamping the support plates fixedly to the pivot means.

3. A mounting for rock drills, comprising a frame, a guide column, a rock drill slidable thereon, support plates on opposite sides of the column and being swingable through the horizontal plane of the frame, and a plurality of pivot means spaced along the length of the support plates for connecting the support plates to the frame and the column.

4. A mounting for rock drills, comprising a frame, a guide column, a rock drill slidable thereon, support plates swingable in vertical planes on opposite sides of the column and having a coniform aperture in each end, coniform trunnions on the column seating into the apertures at one end of the plates, bolts for clamping the plates to the trunnions, coniform disks seating into the other apertures, and bolts in the frame for clamping the disks fixedly to the plates and for clamping the plates fixedly to the frame.
